(57) **CLAIM**

The ornamental design for a game controller cradle for portable devices, as shown and described.

DESCRIPTION

FIG. 1 is a perspective view of a game controller cradle for portable devices showing our new design;

FIG. 2 is a rear elevational view thereof;

FIG. 3 is a front elevational view thereof;

FIG. 4 is a right side elevational view thereof;

FIG. 5 is a top plan view thereof;

FIG. 6 is a bottom plan view thereof; and,

FIG. 7 is a perspective view thereof, shown in environmental use.

The broken lines showing environment are for illustrative purpose only and form no part of the claimed design.
